UNITED STATES PATENT OFFICE.

JOSEPH SZUCHY, OF PERTH AMBOY, NEW JERSEY.

TRAIN SIGNALING AND CONTROLLING SYSTEM.

Application filed June 19, 1923. Serial No. 646,486.

This invention relates to improvements in safety devices for railways in order to prevent collisions and is specially adapted herein to electric locomotives although the principles disclosed could be readily applied to steam locomotives by those skilled in the art.

An object of my invention is to provide an apparatus carried by the locomotive that will automatically operate to stop a train whose engineer has disregarded a danger signal, as for example, a semaphore set against him, manually, or automatically by a train in the preceding block.

Another object is to provide means for stopping the train in a gradual manner with a view to the comfort of the passengers which is attained by several interrupted applications of the brake in conjunction with the shutting off of the power, prior to a final application of sufficient duration to completely stop the train.

Another object is to provide, in addition to the automatic brake application, signals both visible and audible to the engineer which are operated simultaneously with each application of the brakes and likewise interrupted several times which emphasizes further their effectiveness.

Still another object is the provision of means for automatically restarting the train such restarting mechanism being controlled by the train ahead and thereby operated after that train has cleared the forward block.

Further objects will presently appear throughout the following descriptions, the invention consisting of details of construction and in the arrangement and combination of the parts as will be more fully hereinafter pointed out and described.

In the accompanying drawings forming a part hereof,

Fig. 1 is a side elevation of an electric locomotive equipped with my flexible shoes and controlling mechanism connecting with the power circuit and air brake apparatus.

Fig. 2 is an enlarged vertical section through the casing of the controlling mechanism as indicated in the line 2—2 of Fig. 3 with the parts within shown in elevation.

Fig. 3 is a plan view of Fig. 2 with the casing broken out.

Fig. 4 is a vertical section on the line 4—4 of Fig. 3.

Fig. 5 is a similar view on the line 5—5 of Fig. 3.

Fig. 6 is an enlarged elevation of the lower portion of Fig. 1.

Fig. 7 is an end elevation of Fig. 6 as viewed from the right.

Fig. 8 is a horizontal section on the line 8—8 of Fig. 7.

Fig. 9 is a plan view of a portion of a railroad track provided with special signal rails and with my controlling mechanism shown diagrammatically applied thereto in connection with an electric locomotive and,

Fig. 10 is an elevation of a semaphore electrically related to my controlling mechanism and with the lower portion shown in section disclosing the operating mechanism.

Referring to the drawings 1 and 2 designate the usual parallel track rails arranged in sections to provide blocks by insulation 3 electrically separating rail 1 of a block 4 from the continuing rail 5 of a succeeding block 6. The usual power rail for electrically driven trains is indicated at 7 and a series of special rails 8, 9 and 10 separated from each other and of progressively increasing length relative to the direction of travel of the train, are shown secured midway between the rails 1 and 2.

These rails are electrically connected in parallel by a conductor 11 forming part of a circuit including a battery 12.

From the battery 12 a conductor 13 enters a casing 14 of a semaphore 15 and is connected to a cylinder 16 for pneumatically operating the semaphore.

Electrically connected through the cylinder and the mechanism thereof is a contact 17 secured to a rod 18 for actuating the semaphore 15.

Another contact 19 yieldable to compensate for excessive movement of the rod 18 is secured to and insulated from the cylinder 16.

A conductor 20 leads from the contact 19 and is connected to rail 1 of block 4.

When the semaphore 15 is down as shown in Fig. 10 the contacts 17 and 19 are separated and the above circuit is broken but when the semaphore 15 is up as shown in Fig. 9 the circuit is re-established by engagement of the contacts 17 and 19.

My controlling mechanism, carried by a train entering block 4 will now be actuated when contact is made by said train with any one of the rails 8, 9 or 10 and in a manner to be subsequently described herein.

To illustrate the operation of the sema-

phore apparatus, let us assume that the semaphore is held in lowered position as shown in Fig. 10 by the air pressure underneath the piston 68, both valves 62 and 63 being closed. As soon as the locomotive enters the block 6 the magnet 64 will be energized since the two free ends 80 and 81 of its circuit, Fig. 10, are connected to the two tracks in the block 6, as at 80' and 81', Fig. 9, and, in consequence, the set of contacts 65 will be swung to engage the set of contacts 66, energizing the magnet 67 and turning the valve 62, so that the compressed air underneath the piston 68 may escape. Then, under the influence of the spring 69, the semaphore 15 is elevated at once, giving warning that the block is closed. Under the downward course of the piston 68 and connecting rod 18 therefor the contact 17 will be engaged with the contact 19, to close the circuit including the signal rails 8, 9 and 10. When the locomotive leaves the block, the magnet 64 is de-energized so that the set of contacts 65 are re-engaged with the set of contacts 65^a and since the plate 70 is now in engagement with the detent conductor 71, a circuit is completed with the magnet 72 which is energized to open the valve 63. The compressed air then flows underneath the piston 68 and again lowers the semaphore 15. In this connection it will be observed that when the contacts 65 are disengaged from the contacts 66 the magnets 67 will be de-energized, permitting the spring pressed core to drop so as to close the valve 62 which operation is accomplished just a moment before the energization of the magnet 72. When the compressed air has raised the piston 68 to its limit, the detent conductor 71 will ride upon the non-conducting plate 73, breaking the circuit and de-energizing the magnet 72, so that the spring pressed core thereof may operate to close the valve 63. Moreover, it will be observed that under the upward movement of the rod 18, the contact 17 will be drawn out of engagement with the contact 19, breaking the circuit including the signal rails 8, 9 and 10. The pipe line 63' leading to the valve 63 is connected to a suitable source of fluid pressure, and a relatively narrow auxiliary pipe line 82 leads from the same directly to the cylinder 16, opening underneath the piston 68 and keeping up the air pressure therein against the natural leakage when the piston is in its upper position, while permitting an unhindered removal of the air through the valve 62. In Fig. 1 an electric locomotive 21 is shown equipped with my controlling mechanism indicated at 22 and with a pair of contact shoes 23 and a special rail shoe 24, the former engaging the power rail 7 and the latter the signal rails 8, 9 or 10.

These shoes are of special construction to provide an extremely flexible contact member.

They are suspended from the frame of the locomotive 21 in brackets 25 and are provided at their front and rear ends with pairs of upwardly extending arms 26 and 27 terminating in tips 28 and 29 bent at right angles in diametrically opposed relation with respect to each pair of arms, said tips 28 constituting hooks adapted to loosely engage the brackets 25 and be supported thereby.

A spring 30 is interposed between the brackets 25 and the shoes 23 and 24 and tends to hold the shoes downwardly in contact with the rails.

This construction, as will be readily observed, will permit the shoes to move freely in a universal manner and will ensure a more positive and continuous contact of the shoes with their respective rails. Brushes 31 are provided in front of each shoe to remove any obstruction from the power or signal rails.

Referring to Figs. 2, 3, 4, and 5, 32 is a casing within which is the controlling mechanism 22 comprising a series of electric magnets 33 secured to the wall of said casing and adapted to operate an armature 34 pivoted to a bracket 35 and provided with a spring 36 for restoring it to normal position.

Connected to the armature 34 are a pair of links 37 pivoted to crank arms 38 which are secured to a valve 39 and which are adapted to oscillate said valve when the armature 34 is oscillated.

The valve 39 is provided with a passage way 40 and is surrounded by a casing 41 which is interposed in a pipe line 42, one end of which is connected to the train pipe 43 and the other end 42' of which leads to atmosphere through openings 44 in the valve casing 41 so that when the valve 39 is rotated and the passage 40 is brought into registration with said openings the train pipe will be opened with the consequent application of the brakes 45 in the usual well known manner. In Fig. 9 I show in a diagrammatic way the connection of my train pipe line bleeding and brake operating line 42 with a usual train compressed air pipe line 43 and a Westinghouse air brake 94. In the diagrammatic showing the character 90 indicates the air tank of the brake, 91 the brake cylinder, 92 the operating rod connected with the brake shoes 45, 93 the control valve, and 42' the usual lead to the atmosphere. It is obvious that permitting the compressed air to escape through line 42 will set the brakes in operation, while the closing of line 42 will build up the pressure in the control valve chamber and will cause the brake to be released by the action of its spring, as is well known in the art.

Another pair of links 46, similar to links 37, are connected to the armature 34 and are pivoted to crank arms 47 between which and secured thereto is a rod 48 extending within casing 49 and provided with an arm 50 constituting a movable contact member adapted to contact with a fixed contact member 51 insulated from said casing 49.

Conductors 52 and 53 lead from said contact members to the controller box 54 of the locomotive 21 and form an open circuit which when closed by the movement of armature 34 and the consequent contacting of members 50 and 51 will operate a circuit breaker 55 within said controller box, whereby the power circuit 55 will be broken to stop the train motor 56. A diagrammatic view of the controller box and the circuit breaker therein is shown in Fig. 9. The main or power current reaches the controller box as at 83, passes through a contact maker and breaker 86, normally held in closed position by a spring 87, passes through the regular controller cylinder 85, operated by the crank 88, and leaves through the usual variable resistance contacts 84 into line 55 and motor 56. The auxiliary or signal current enters the controller box as at 52' passes through an electromagnet 89, operating the contact maker and breaker 86, and leaves through the lines 52 and 53 when the contacts 50 and 51 are closed in box 49.

This all takes place as above described when the contact shoe 24 engages either of the rails 8, 9, or 10 the shoe 24 having a conductor 57 leading therefrom through the controlling mechanism 22 to a grounded connection in the locomotive whereby an energized circuit will be established as follows:—

From the battery 12 through conductor 11 to a signal rail 9 (see Fig. 9) through contact shoe 24 to conductor 57 to electromagnets 33 to conductor 58, to ground and from ground to conductor 20 to semaphore contacts 17 and 19 and thence to battery through conductor 13.

Connected in parallel with the electromagnets 33 is a signal bell 59 and in series a signal light 60 constituting an audible and a visible warning signal to the engineer of the presence of a train in the block in advance also that his brakes and power have been influenced by the automatic controlling mechanism.

Instead of operating a circuit breaker in an electric locomotive it is conceivable that the closing of the contacts 50 and 51 could operate electrically, a throttle of a steam locomotive which in conjunction with the application of the brakes in a manner above described would also stop a locomotive of this character and a train attached thereto.

Referring to Fig. 9 and more particularly to rails 8, 9 and 10 which it will be noted are of progressively increasing length with re-

spect to direction of travel of the train as indicated by the arrow, these rails are separated from each other and are of suitable proportion for the purpose of gradually stopping the train contacting with them, providing, of course, there is a reason for such stopping which has closed the circuit for operating the stopping mechanism.

When rails 8 is engaged there will be a brief application of the brakes of a duration proportionate to the length of said rail and simultaneously with the shutting off of the train power but all of which will be insufficient to completely stop the train running at regular speed simply serving to check the speed and warn the engineer by means of the signals 59 and 60 as to what is happening.

When the shoe 24 leaves the rail 8 and before reaching the rail 9 the circuit within the locomotive is de-energized again for a brief period but when the longer rail 9 is reached there will be a proportionately longer application of the brakes and an interruption of the power for a corresponding period until finally the rail 10 is reached.

This is of sufficient length to completely stop the train upon that corresponding section of track way.

Under no condition can this train be restarted while the semaphore 15 is in the position shown in Fig. 9 but as soon as the train in the block 6 in advance leaves said block the contacts 17 and 19 will again be separated de-energizing the circuit and releasing the armature 34 so that the spring 36 will move it and the train pipe line will again be closed to release the brakes. Then the power circuit will be re-established permitting the train to proceed to the next block 6.

It will be seen that I have described one embodiment of the invention many features of which, including matters of arrangement, design, combination and detail, may be variously modified without departing from the underlying principles and it is not intended to limit the invention to such features except in so far as set forth in the appended claims.

What is claimed is:

1. In a train signaling and controlling system for electric trains in which the track-way is divided into a series of blocks electrically interrelated, each of said blocks being provided with a semaphore the operation of which is controlled by a train in the block in advance, a series of separated signal rails of progressively increasing length with respect to the direction of travel of the train said rails being electrically connected and forming a portion of an electric circuit normally open, and means for closing said circuit operated by the train in the block in advance simultaneously with the actuation of the semaphore thereby, a circuit carried by the train in the block following the one in

- advance, and means carried by said train adapted to be electrically operated when a contact member on said train successively engages said signal rails thereby successively connecting said circuit with said semaphore circuit and successively establishing an energized circuit whereby the current driving said train will be alternately interrupted and reestablished corresponding with the successive engagement with the said rails and the brakes thereby alternately applied and released and the speed of the said train reduced accordingly, the final signal rail being of sufficient length to stop the said train.
2. In a train signaling and controlling system for electric trains in which the track-way is divided into a series of blocks electrically interrelated, each of said blocks being provided with a semaphore the operation of which is controlled by a train in the block in advance, a series of separated signal rails of progressively increasing length with respect to the direction of travel of the train said rails being electrically connected and forming a portion of an electric circuit normally open, and means for closing said circuit operated by the train in the block in advance simultaneously with the actuation of the semaphore thereby, a circuit carried by the train in the block following the one in advance, and means carried by said train adapted to be electrically operated when a contact member on said train successively engages said signal rails thereby successively connecting said circuit with said semaphore circuit and successively establishing an energized circuit whereby the current driving said train will be alternately interrupted and re-established corresponding with the successive engagement with the said rails and the brakes thereby alternately applied and released and the speed of the said train reduced accordingly, the final signal rail being of sufficient length to stop said train, and means for re-establishing the flow of driving current and for releasing said brakes to restart said train.
3. In a train signaling and controlling system for electric trains in which the track-way is divided into a series of blocks electrically interrelated, each of said blocks being provided with a semaphore the operation of which is controlled by a train in the block in advance, a series of separated signal rails of progressively increasing length with respect to the direction of travel of the train said rails being electrically connected and forming a portion of an electric circuit normally open, and means for closing said circuit operated by the train in the block in advance simultaneously with the actuation of the semaphore thereby, a circuit carried by the train following the one in advance, and means carried by said train comprising an electro magnet, an armature for said magnet, an air valve and a switch operatively connected to said armature and adapted to be opened and closed respectively and simultaneously when a contact member on said train engages said signal rails to close said train carried circuit and connect same with said semaphore circuit to establish an energized circuit and thereby energize said electromagnet to move said armature whereby the successive engagement of said train carried contact member with said rails will successively operate said armature to thereby cause a corresponding successive interruption of the flow of power current to said train and a successive application of the brakes to check the speed of said train, the final signal rail being of sufficient length to stop said train.

Signed at Perth Amboy, in the county of Middlesex and State of New Jersey, this 28 day of December, 1925.

JOSEPH SZUCHY.
